A. CHRISTIANSON.

SIX WHEEL TRUCK.

APPLICATION FILED JULY 25, 1916.

1,255,857.

Patented Feb. 12, 1918.

UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

SIX-WHEEL TRUCK.

1,255,857.

Specification of Letters Patent. Patented Feb. 12, 1918.

Application filed July 25, 1916. Serial No. 111,159.

To all whom it may concern:

Be it known that I, ANDREW CHRISTIANSON, a citizen of the United States, and resident of Butler, in the county of Butler and 5 State of Pennsylvania, have invented a new and useful Improvement in Six-Wheel Trucks; and I do hereby declare the following to be a full, clear, and exact description thereof.

10 My invention relates to six-wheel car trucks.

The object of my invention is to provide a simple and efficient means for equalizing the weights on the different pairs of wheels 15 so that the weight is distributed substantially equally on the outside and middle wheels, whereby the riding qualities of the car are greatly improved and the amount of repair work greatly reduced.

20 To these ends my invention comprises the novel features hereinafter set forth and claimed.

In the accompanying drawing, Figure 1 is a plan view of a portion of a six-wheel truck, partly broken away, showing my invention applied thereto; Fig. 2 is a part 25 longitudinal section of same; Fig. 3 is a section on the line 3—3, Fig. 1; Fig. 4 is a modified form of my invention; and Fig. 30 5 is a section on the line 5—5, Fig. 1.

In the drawing, I have illustrated my invention in connection with a well-known 35 form of passenger car truck-frame of the six-wheel type, said frame consisting of the wheel-pieces 2, the end-rails 3, the transoms 4, and wheel-pieces 5. The wheel-piece 2, as shown, is substantially box-shape in cross-section and comprises a top-plate 10, an inner-wall 11, an outer wall 12, and a bottom-plate 13. The front-wall or outer wall 40 12 is provided with the opening 14, which is closed ordinarily by the plate 15 secured in place by bolts 16.

The bottom-plate 13 is provided with the 45 openings 17 registering with the journal-boxes 18. Supported on the journal-boxes 18 are the blocks 19, which form the supports for the ends of the equalizer-bars 20.

The blocks 19 may be slightly concaved as 50 at 21 to receive the curved end-portions 22 of the equalizer-bars.

A bolt or hanger 23 is suspended from the equalizer-bar at one side of the mid-point of said bar. This hanger is suspended a 55 from a pin 24, which passes through a

clevis 25 on the upper end of the hanger, as clearly indicated in Fig. 3. The opening 26 in the clevis 25 is slightly larger than the pin 24 to allow for a certain amount of play for the reason more fully herein- 60 after set forth.

The hanger 23 passes down through a suitable opening 27 formed in the bottom-piece 13 of the wheel-piece 2, said opening being large enough to permit of a certain 65 amount of movement of said hanger herein.

A bearing-plate 28 bears against the seat 29 around the opening 27, said bearing-plate having the neck-portion 30, which enters said opening. The bearing-plate 28 is 70 provided with the opening 31 for the passage of the hanger.

Surrounding the hanger is the spring-plate 32 held in place by the nut 33 engaging the threaded portion 34 of the hanger. 75 Springs 35 are interposed between the bearing-plate 28 and the spring-plate 32, the tension of said springs being controlled by the position of the nut 33 on the hanger. The springs 35 act normally to hold the 80 equalizer-bars 20 down on the journal-boxes and by the use of said springs a yielding or cushion-fulcrum is provided between the equalizer-bar and the truck side-frame.

The truck is provided with the ordinary 85 leaf-springs 36 supported in the usual manner between the pairs of wheels.

When the truck is in use and a strain is brought to bear on the front-wheels so that the front end of the equalizer-bar is lowered, the cushion-fulcrum will act to distribute the load on the other wheels so as to equalize the weights on the different pairs of wheels thereby greatly improving the riding quality of the car. The suspended 90 hanger permits of the swinging of the same due to this raising or lowering of the ends of the equalizer-bar; and furthermore, the equalizer-bar is contained within the truck-frame, which reduces the size and weight 100 of the equalizer-bar while, at the same time, it is out of the road for removal and application of brake-shoes.

Another point of advantage of a yielding-fulcrum of this type in the riding of the 105 truck consists of the breaking up of the vibrations; that is, the fulcrum spring being a spring of short period of vibration and the elliptic springs 36 under the truck-bolsters being of long period oscillation. 110

In Fig. 4, I have illustrated a modified form of my invention in which the hanger instead of having the clevis-end 25 has simply a straight end-portion through which the connecting pin passes. This construction permits of the use of an inner-plate 37 acting to strengthen or brace the wheel-piece 2.

What I claim is:

- 10 1. The combination with a truck-frame and its journal-boxes, of an equalizer-bar supported at its ends on said journal-boxes, a hanger suspended from said equalizer-bar, and a spring interposed between an abutment on said hanger and said frame, whereby a yielding-fulcrum is formed between the truck-frame and said equalizer-bar.
- 15 2. The combination with a truck-frame and its journal-boxes, of an equalizer-bar supported at its ends on said journal-boxes, a hanger suspended from said equalizer-

bar; an abutment on said hanger, a bearing-plate surrounding said hanger bearing against said frame, and a spring interposed between said abutment and said bearing-plate, whereby a yielding-fulcrum is formed between said frame and said equalizer-bar. 25

3. The combination of a truck frame having a hollow wheel-piece, journal-boxes, an equalizer-bar contained within said hollow wheel-piece and its ends bearing on said journal-boxes, and a spring-controlled hanger depending from said equalizer-bar and forming a yielding fulcrum between said frame and said equalizer-bar. 30

In testimony whereof, I the said ANDREW CHRISTIANSON, have hereunto set my hand.

ANDREW CHRISTIANSON.
